SOOT BLOWER

Ivan D. Eby, Richmond, N. Y.

Application April 18, 1930. Serial No. 445,257

13 Claims. (Cl. 122—391)

The present invention relates to soot blowers and is more particularly directed toward soot blowers adapted for use in high pressure boilers, such as marine boilers.

5 The present invention contemplates a soot blower adapted to occupy one of the fire tubes of the boiler and to be actuated from the front of the boiler without opening the smoke box door or shutting down the furnace. According to the 10 present invention, the soot blower passes through the smoke box door, one of the boiler tubes and into the combustion chamber at the rear of the boiler. The soot blower has a single nozzle adapted to produce a strong oblique jet of 15 steam directed against the rear tube head.

The invention also contemplates a soot blower which has provision for blowing the front tube sheet and the superheater tubes above and in front of the boiler. As the soot blower contemplated by the present invention is to be left in the furnace when not in use, the present invention contemplates the provision of an easy detachable coupling member by which the soot blower may be coupled to a steam hose connection, designed to permit manual rotation of the 25 pipe and blower head.

The invention also contemplates the provision of suitable means to insure the gradual feeding in of the soot blower as it is turned in the 30 boiler tube, this means being in the form of a friction drag carried by the smoke box door.

Other and further objects of the invention will appear as the description proceeds.

The accompanying drawing shows, for purposes 35 of illustrating the invention, one embodiment in which the invention may take form, it being understood that the drawing is illustrative of the invention rather than limiting the same.

In this drawing:

40 Figure 1 is a diagrammatic sectional view through a boiler showing the soot blower and operating connections in place;

Figure 2 is a longitudinal sectional view of the 45 soot blower and operating connections with parts broken away;

Figure 3 is an elevational view taken in the direction of the arrow 3 of Figure 1, showing the devices carried by the smoke box door; and

Figure 4 is a central sectional view on the line 50 4—4 of Figure 3.

In Figure 1 a portion of a conventional marine type boiler is shown. It has a bank of tubes indicated at 10, a combustion chamber 11 at the rear, a smoke box 12 at the front closed by a 55 smoke box door 13, and the usual superheater 14 above the smoke box.

The soot blower head is indicated at 20. This soot blower head may be made of cast steel and is provided with Monel metal venturi 21 of large 60 diameter and set at an angle of about 45°, so as

to create an exceedingly strong concentrated jet of steam to be sent out in an oblique direction. The blower head 20 is threaded as indicated at 22 so as to accommodate a length of pipe 23. This pipe is long enough to extend beyond the 65 smoke box door, the left end being threaded as indicated at 24 to fit a coupling member 25. It will, of course, be understood that more than one piece of pipe may be employed with an ordinary coupling.

This pipe 23 is provided with a hole 26 opposite the nozzle 21 and spaced from this nozzle so that the hole will be near the front tube sheet when the soot blower head is at the rear of a combustion chamber, as shown in the drawing.

The coupling part 25 is turned out as indicated at 27 and threaded at 27 to receive a coupling part 28. These are running threads instead of pipe threads, and the coupling parts 25 and 28 make up against a shoulder 29. The coupling part 28 is threaded at the left, as indicated at 30, to receive a tube 31. This tube may be made of extra heavy seamless pipe and is turned down to provide shoulders indicated at 32 and 33. This pipe or tube 31 is insertable from the right 85 into a casing or housing 34 having a shoulder 35 engageable with the shoulder 33 on the tube.

The housing 34 has an internally threaded boss 36 for connection with a steam hose 37, and is slightly enlarged, as indicated, so as to 90 form a chamber and pass the steam to the ports 38 cut in the side walls of the tube 31. The housing 34 is threaded at the right or inner end, as indicated at 39, to accommodate a gland nut 40. This gland nut 40 acts on a packing ring 95 41 to force packing 42 down against a retaining ring 43. This retaining ring engages the shoulder 32. The other end of the housing 34 is threaded, as indicated at 44, to receive a gland nut 45 which acts on a packing ring 46 to force 100 packing 47 down against the shoulder 48 on the housing 34. The pipe 31 extends through the gland nut 45 and carries a sprocket wheel or other turning mechanism, as indicated at 49. The exposed end is plugged as indicated at 50. 105

The smoke box door has an opening to accommodate the soot blower. The details of this opening and the associated mechanism is shown in Figures 3 and 4. The plate of the smoke box door may be cut with a torch to provide a round 110 opening 51, and a heavy iron ring 52 is secured to the smoke box door with its center approximately in line with the tube which is to carry the soot blower. The ring 52 has a comparatively large opening and is provided at the sides with 115 upwardly extending chocks 53 and 54 adapted to receive lateral extensions 55 and 56 carried by the upper member 57 of a two part ring, the lower part being 58. The lower ring part 58 has side lugs 59 to accommodate bolts 60 threaded 120

into enlargements 61 on the upper ring part 57. Springs 62 tend to hold the two ring parts 57 and 58 close together, as indicated in Figure 3. The lower rear edge of the upper half ring 57 is extended downwardly, as indicated at 63, so as to come behind the lower plate half 58 and close off the slot between the ring parts when separated far enough to accommodate the pipe. This prevents steam and soot from blowing 10 through into the boiler room. It is, of course, obvious that the lower half of the ring may be the part supported by the fixed ring and that the upper half of the ring may be squeezed against the blower pipe.

15 In installing the soot blower and the boiler, the blower head and pipe are inserted through the smoke box door and the boiler tube or the blower head threaded onto the pipe in the combustion chamber. The two part ring 57-58 is secured 20 in place and, at this time, the springs 62 will be tensioned by the spreading of these two parts. The extent of opening, however, is not sufficient to move the lower plate beyond the lower edge of the depending projection 63 carried by the 25 upper plate part. These springs 62 squeeze the pipe 23 and make a fairly tight joint all the way about the pipe, thereby preventing soot from blowing out through the opening in the smoke box door. The coupling 25 is secured to the pipe 23 outside the smoke box door and this much of the outfit may be allowed to remain in the furnace with the soot blower head in the position indicated in dotted lines.

When it is desired to blow the boiler, the hose 35 connection 34, with the coupling part 28 carried thereby, is brought into line with the soot blower pipe. The coupling parts easily telescope, and the hand wheel or sprocket wheel 49 is then turned to thread the parts 25 and 28 together. 40 The clamping action of the closure device on the smoke box door holds the pipe 23 against rotation so as to permit making up a tight joint.

With the parts in the dotted line position, steam is turned on and this will cause a strong 45 jet of steam to blow against the rear tube sheet and a smaller jet of steam to blow in the smoke box. As the device is turned, the jet of steam on the rear tube sheet blows different tubes, and, owing to the reaction of the 50 steam there is a tendency for the soot blower to move toward the rear of the boiler. This tendency is resisted by the clamping action of the devices carried by the smoke box door. This clamping action, however, is not sufficient 55 to prevent the inward movement of the soot blower but is sufficient to cause a gradual threading in of the blower. This threading in or advancing of the soot blower is brought about without any actual threading of the parts. 60 The opening 26 is opposite the nozzle 21 so that there will be no attempt to blow a tube from both directions at once. This will cause a better circulation of steam in the passages and will assist in blowing the soot out of the 65 boiler.

Where a number of boilers are in use, one steam hose connecting device is all that is necessary for the number of soot blowers, and, in this case, the steam hose connection 34 is carried from an overhead trolley 70 extending across the boiler room. When it is desired to remove the hose connection from the soot blower, it is merely necessary to turn the wheel 49 backward. As considerable resistance is offered 75 to the movement of the pipe 23 on account of

the gripping of this pipe and the friction with the inside of the boiler tube, the parts may be readily unthreaded.

No interference to turning the blower need arise because the two part ring 57 and 58 can raise and lower or move sidewise to a slight amount to take care of any irregularities or misalignment of parts. The arrangement provided, furthermore, makes it possible to open the smoke box door, as indicated in dotted lines, without interference by the soot blower. To do this the parts 57 and 58 may be slipped away from the chocks, as the door is partly opened, thereby leaving the large opening in the rings 52.

It is obvious that the invention may be embodied in many forms and constructions, and I wish it to be understood that the particular form shown is but one of the many forms. Various modifications and changes being possible, I do not otherwise limit myself in any way with respect thereto.

What is claimed is:

1. In combination, a boiler having a smoke box door, smoke chamber, bank of fire tubes and combustion chamber at the rear of the fire tubes, a soot blower comprising a pipe extending from the front of the smoke box door through one of the tubes into the combustion chamber, and a blower head carried by the inner end of the pipe and having a nozzle to create an oblique jet of steam directed toward the rear tube sheet of the boiler, the pipe being rotatable in the tube and reciprocable along the tube so that the jet of steam from the blower head may be directed toward various parts of the rear tube sheet, the pipe having a hole in the portion thereof in the smoke box adapted to be brought close to the front tube sheet when the blower head is in the rear of the combustion chamber, said hole being adapted to emit a strong jet into the smoke box so as to blow the front tube sheet and smoke box while the tubes are blown from the rear by the jet from the blower head.

2. In combination, a boiler having a smoke box door, smoke chamber, bank of fire tubes and combustion chamber at the rear of the fire tubes, a soot blower comprising a pipe extending from the front of the smoke box door through one of the tubes into the combustion chamber, and a blower head carried by the inner end of the pipe and having a nozzle to create an oblique jet of steam directed toward the rear tube sheet of the boiler, the pipe being rotatable in the tube and reciprocable along the tube so that the jet of steam from the blower head may be directed toward various parts of the rear tube sheet, the pipe having a hole in the portion thereof in the smoke box adapted to be brought close to the front tube sheet when the blower head is in the rear of the combustion chamber, said hole being adapted to emit a strong jet into the smoke box so as to blow the front tube sheet and smoke box while the tubes are blown from the rear by the jet from the blower head, the hole and nozzle being angularly disaligned so that steam and soot may be blown forward through the tubes by the jet from the nozzle without interference by the steam jet in the smoke box.

3. In combination, a boiler having a smoke box door, smoke chamber, bank of fire tubes and combustion chamber at the rear of the fire tubes, a soot blower comprising a pipe extending from the front of the smoke box door through one of the tubes into the combustion chamber, and a blower head carried by the inner end of the pipe

- and having a nozzle to create an oblique jet of steam directed toward the rear tube sheet of the boiler, the pipe being rotatable in the tube and reciprocable along the tube so that the jet 5 of steam from the blower head may be directed toward various parts of the rear tube sheet, the pipe having a hole in the portion thereof in the smoke box adapted to be brought close to the front tube sheet when the blower head is in the 10 rear of the combustion chamber, said hole being diametrically opposite the nozzle and adapted to emit a strong jet into the smoke box so as to blow the front tube sheet and smoke box while the tubes are blown from the rear by the jet 15 from the blower head.
4. In combination, a boiler having a smoke box door, smoke chamber, bank of fire tubes and combustion chamber at the rear of the fire tubes, a soot blower comprising a pipe extending from 20 the front of the smoke box door through one of the tubes into the combustion chamber, and a blower head carried by the inner end of the pipe and having a nozzle to create an oblique jet of steam directed toward the rear tube sheet of the 25 boiler, the pipe being rotatable in the tube and reciprocable along the tube, a steam hose connection in front of the smoke box door, means for coupling the hose connection to the pipe so that the pipe may rotate relating to the hose 30 connection, and an adjustable friction device carried by the smoke box door to resist the thrust produced by the jet issuing from the blower head.
5. In combination, a boiler having a smoke box door, smoke chamber, bank of fire tubes and combustion chamber at the rear of the fire tubes, a soot blower comprising a pipe extending from 35 the front of the smoke box door through one of the tubes into the combustion chamber, and a blower head carried by the inner end of the pipe and having a nozzle to create an oblique jet of steam directed toward the rear tube sheet of the 40 boiler, the pipe being rotatable in the tube and reciprocable along the tube, a steam hose connection in front of the smoke box door, means for coupling the hose connection to the pipe so that the pipe may rotate relating to the hose 45 connection, and a friction clamp carried by the smoke box door for retarding the longitudinal 50 movement of the pipe as the pipe is turned on its axis to revolve the steam jet.
6. In combination, a boiler having a smoke box door, smoke chamber, bank of fire tubes and combustion chamber at the rear of the fire tubes, a soot blower comprising a pipe extending from 55 the front of the smoke box door through one of the tubes into the combustion chamber, and a blower head carried by the inner end of the pipe and having a nozzle to create an oblique jet of steam directed toward the rear tube sheet of the 60 boiler, the pipe being rotatable in the tube and reciprocable along the tube, a two part friction collar surrounding the pipe and supported thereby in front of the smoke box door, spring 65 means for squeezing the two parts of the friction collar toward one another to cause the collar parts to grip the pipe, and means coupled to the pipe for rotating the pipe and admitting steam to it.
7. A friction drag for soot blowers employing 70 a rotatable and reciprocable length of pipe lead-
- ing to a blower head having a nozzle constructed to discharge cleaning fluid in a direction such that a re-active force is imparted to the pipe in the direction of its length, comprising a stationary abutment, a pair of spring pressed blocks 80 about the pipe and adapted to grip the pipe, the blocks being disposed in front of the stationary abutment and permitting the gradual threading of the pipe as it is rotated during the time cleaning fluid is applied to said nozzle.
8. In combination, a soot blower having a rotatable and reciprocable length of pipe leading to an oblique nozzle which produces thrust tending to draw the blower into the fire box of a boiler, and an adjustable friction drag which 85 grips the pipe and resists the thrust sufficiently to insure a gradual threading in of the blower as it is turned.
9. A smoke box door closure device for soot blowers, comprising a ring adapted to be carried by the smoke box door in approximate alignment with a boiler tube, a two part plate 90 adapted to close the opening in the ring and having an opening to accommodate the pipe of the soot blower, and spring means to squeeze 100 the plate parts against the blower pipe.
10. A smoke box door closure device for soot blowers, comprising a ring adapted to be carried by the smoke box door in approximate alignment with a boiler tube, a two part plate 105 adapted to close the opening in the ring and having an opening to accommodate the pipe of the soot blower, and spring means to squeeze the plate parts against the blower pipe, the ring and plate having cooperative means to support 110 the plate in the absence of a blower pipe.
11. A smoke box door closure device for soot blowers, comprising a ring adapted to be carried by the smoke box door in approximate alignment with a boiler tube, a two part plate 115 adapted to close the opening in the ring and having an opening to accommodate the pipe of the soot blower, and spring means to squeeze the plate parts against the blower pipe, the ring and plate having cooperative means to support the plate 120 in the absence of a blower pipe, the ring having upwardly opening chocks and one of the plate parts having side numbers received in the chocks and adapted to support the ring in the absence of a blower pipe.
12. In combination, a soot blower having a rotatable and reciprocable length of pipe leading to an oblique nozzle which produces thrust tending to draw the blower into the fire box of a boiler, and an adjustable friction drag which 130 grips the pipe and resists the thrust sufficiently to insure a gradual threading in of the blower as it is turned, one plate part being extended to be behind the other plate part and close off the joint between the plate parts and prevent the 135 blowing of steam and soot through the joint.
13. The method of blowing fire tube boilers having a combustion chamber at the rear and a smoke box at the front, which consists in simultaneously producing revolvable jets in both the smoke box and combustion chamber disaligned from one another so that the blowing of pipes by the rear jet is accomplished without interference by the front jet.

IVAN D. EBY. 145
